UNITED STATES PATENT OFFICE

RUDOLF SCHUBERT, OF EASTON, PENNSYLVANIA

WINDOW SASH LOCK

Application filed May 12, 1932. Serial No. 610,858.

My invention relates to window sash locks, and it relates more particularly to a lock adapted to be used in connection with the ordinary type of window construction, in which a pair of sash are mounted in a frame so as to be vertically slidable therein, the lock being adapted to secure the lock with one or both of said sash in a partially open position.

The principal object of my invention is to provide a simple and efficient lock for sliding window sash, which may be readily applied to the common form of window construction at present in use, which will permit the sash to be secured in intermediate positions against undesired movement.

A further object of my invention is to provide a window sash lock of the character aforesaid, which is so constructed and arranged as to ordinarily fasten the sash by frictional engagement, but which will bring about a positive engagement in the event of improper attempts to move the sash from their locked positions.

The nature and characteristic features of my invention will be more readily understood from the following description, taken in connection with the accompanying drawing forming part hereof, in which:

Figure 1 is a fragmentary sectional view of a window structure, illustrating the meeting rails of a pair of sash, one of said rails having the device of my invention mounted thereon, the parts being shown in their normal locking positions;

Fig. 2 is a view similar to Fig. 1, but with the device of my invention shown with the parts in the positions assumed under abnormal conditions, that is to say, when an attempt is made to force the sash from their normally locked positions;

Fig. 3 is a top or plan view of the device of my invention, detached;

Fig. 4 is a vertical, central section thereof; Fig. 5 is a front elevation thereof; and

Fig. 6 is a side elevation of a modified form of the device.

Referring now more particularly to Figs. 1 to 5 of the drawing, 10 is a window frame of the usual type, in which the upper sash 11 and lower sash 12 are slidably mounted.

13 is the lower or meeting rail of the upper sash, and 14 is the upper or meeting rail of the lower sash.

The device of my invention, shown in detached detail in Figs. 3, 4, and 5 of the drawing, is preferably mounted on the upper rail 14 of the lower sash, and positioned so that a portion thereof, as will be hereinafter explained, will engage the side stile 15 of the upper sash. If desired, one of the devices 60 may be mounted on each side of the window structure.

The device preferably comprises a supporting bracket 16, the base portion 17 of which is adapted to be secured to the sash by suitable screws, or other fastening devices, extending through the holes 18 provided in the base portion 17 for that purpose.

The bracket member 16 is also provided with a pair of upwardly extending walls 19, between which a clamping member 20 is tiltably mounted by means of a pivot pin 21.

The upper portion of the front end of the clamping member 20 is hollowed out, as at 22, for the mounting therein of a friction roller 23, which is secured in place by means of a suitable pin 24. The clamping member 20 is also so shaped as to provide a tooth 25 immediately above the friction roller 23, for a purpose to be presently explained.

The rear end of the clamping member 20 is slotted as at 26, for the mounting therein of a finger lever 27, which is pivotally secured to the clamping member 20 by means of a pin 28. The lower end of the finger lever 27 is provided with a cam surface 29, which bears against the base portion 17 of the bracket member 16, the arrangement being such that when the lever 27 is actuated, the clamping member 20 will be tilted with respect to the bracket member 16, to cause the friction roller 23 to bear against the surface of the side stile 15 of the upper window sash with the desired degree of pressure.

The operation of the device may now be explained. The clamping member 20, and the finger lever 27 for actuating the same, are normally in such positions that the sash may be freely raised and lowered. When, however, it is desired to lock the sash in shifted 100

relationship with respect to each other, (for example with the lower sash slightly raised or the upper sash slightly lowered, for the purpose of ventilation); after the sash are

5 brought to the desired relative positions, the finger lever 27 is manipulated to cause the roller 23 to bear against the side stile of the upper sash sufficiently to cause the sash to be frictionally bound in the grooves in the window frame in which they normally travel.

10 It will be noted that when the clamping member 20 is in the normal locking position, any attempt to move one of the sash with respect to the other will cause the clamping

15 member 20 to be swung still further about the axis provided by the pivot pin 21, and if the degree of force exerted is sufficient to move one of the sash with respect to the other, the clamping member 20 will be swung sufficient

20 to cause the tooth 25 thereof to bite into the side stile 15 of the upper sash, thus positively preventing any further movement of the sash with respect to each other. When this action occurs, the lever 27 will fall by gravity and

25 will thereafter maintain the tooth in its engagement with the side stile of the upper sash, and hold the same therein until it is subsequently released by the proper manipulation of the lever 27.

30 In Fig. 6 of the drawing, there is shown a modified form of the invention, in which each of the side walls 19 of the bracket member 16 is provided with a slot 30 at the lower forward portion thereof. The lower marginal edge of this slot 30 is provided with a plurality of recesses 31 for the alternative positioning therein of the pin 21, thus permitting adjustment of the clamping member 20 to compensate for wear and for irregularity of the window structure.

35 40 I claim:

1. A window sash lock comprising a bracket member, a clamping member pivotally mounted in said bracket member, a member carried by the clamping member adapted to bear against a portion of a window sash to lock said sash, and a finger lever pivotally mounted on the clamping member having a cam surface bearing against a portion of the bracket member and adapted when actuated to swing the clamping member positively to the locking position.

45 50 55 60 65 2. A window sash lock comprising a bracket member, a clamping member pivotally mounted in said bracket member, a smooth surfaced member carried by the clamping member adapted to bear against a portion of a window sash to effect the normal locking of the sash, and a finger lever pivotally mounted with respect to the clamping member having a cam surface bearing against a portion of the bracket member and adapted when actuated to swing the clamping member to the normal locking position; the clamping member having a tooth normally free of

engagement with the window sash but adapted to bite into the same when the sash is shifted when the clamping member is in the normal locking position.

3. A window sash lock comprising a bracket member, a clamping member pivotally mounted in said bracket member, a smooth surfaced member carried by the clamping member adapted to bear against a portion of a window sash to effect the normal locking of the sash and a finger lever pivotally mounted with respect to the clamping member having a cam surface bearing against a portion of the bracket member and adapted when actuated to swing the clamping member to the normal locking position; the clamping member having a tooth normally free of engagement with the window sash but adapted to bite into the same when the sash is shifted when the clamping member is in the normal locking position, and the finger lever being freely pivoted in the clamping member whereby the same will automatically move to a position to maintain the clamping member in the abnormal locking position.

4. A window sash lock comprising a bracket member adapted to be mounted on the upper or meeting rail of the lower sash of a window structure, a clamping member pivotally mounted in said bracket member, a member carried by the clamping member adapted to bear against the side stile of the upper window sash to lock the sash, and a finger lever pivotally mounted on the clamping member adapted when actuated to swing the clamping member positively to the locking position.

5. A window sash lock comprising a bracket member adapted to be mounted on the upper or meeting rail of the lower sash of a window structure, a clamping member pivotally mounted in said bracket member, a smooth surfaced member carried by the clamping member adapted to bear against the side stile of the upper window sash to effect the normal locking of the sash, and the clamping member having a tooth normally free of engagement with the side stile of the window sash but adapted to bite into the same when one of the sash is shifted with respect to the other when the clamping member is in the normal locking position.

6. A window sash lock comprising a bracket member adapted to be mounted on the upper or meeting rail of the lower sash of a window structure, a clamping member pivotally mounted in said bracket member, a smooth surfaced member carried by the clamping member adapted to bear against the side stile of the upper window sash to effect the normal locking of the sash, and a finger lever pivotally mounted with respect to the clamping member having a cam surface bearing against a portion of the bracket member and adapted when actuated to swing the clamping member to the normal locking position.

tion; the clamping member having a tooth normally free of engagement with the side stile of the window sash but adapted to bite into the same when one of the sash is shifted with respect to the other when the clamping member is in the normal locking position.

7. A window sash lock comprising a bracket member adapted to be mounted on the upper or meeting rail of the lower sash of a window structure, a clamping member pivotally mounted in said bracket member, a member carried by the clamping member adapted to bear against the side stile of the upper window sash to effect the normal locking of the sash, and a finger lever pivotally mounted with respect to the clamping member having a cam surface bearing against a portion of the bracket member and adapted when actuated to swing the clamping member to the normal locking position; the clamping member having a tooth normally free of engagement with the side stile of the window sash but adapted to bite into the same when one of the sash is shifted with respect to the other when the clamping member is in the normal locking position, and the finger lever being freely pivoted in the clamping member whereby the same will automatically move to a position to maintain the clamping member in the abnormal locking position.

8. A window sash lock comprising a bracket member, a clamping member, a member carried thereby adapted to bear against a portion of a window sash to lock said sash, a pivot pin for pivotally mounting the clamping member in the bracket member, the bracket member having a series of serrations in which the pivot pin is adapted to be alternatively seated thereby to adjust the position of the clamping member, and a finger lever pivotally mounted in the clamping member adapted when actuated to swing the clamping member to the locking position.

In testimony whereof, I have hereunto signed my name.

RUDOLF SCHUBERT.
